UNITED STATES PATENT OFFICE.

MINNIE K. NORTON, OF MINNEAPOLIS, MINNESOTA.

DESIGN FOR A KETTLE-SCRAPER.

SPECIFICATION forming part of Design No. 26,798, dated March 23, 1897.

Application filed February 5, 1897. Serial No. 622,223. Term of patent 7 years.

To all whom it may concern:

Be it known that I, MINNIE K. NORTON, of the city of Minneapolis, Hennepin county, Minnesota, have invented and produced a new and original Design for a Kettle-Scraper, of which the following is a specification, reference being had to the accompanying drawings, forming a part hereof.

Figure 1 is a perspective view of a kettle-scraper, showing my design. Fig. 2 is a plan view of the same; Fig. 3, an edge view, these three views being deemed necessary to fully illustrate my design.

The leading feature of my design consists in the two straight edges meeting at an acute angle, the ends of said straight edges being connected by a full curve.

The kettle-scraper consists of a metal plate A, having the straight side or edge B, with the straight short edge C meeting the edge B at an acute angle, the corner or point between said two edges being rounded off at D. The

opposite ends of the straight edges B and C are connected by the full and somewhat irregular curve E. The plate A may be provided with the hole, F and, if preferred, with a suitable handle G. (Indicated by dotted lines in Fig. 2.) All of the edges of the plate are preferably rounded off, as shown in Fig. 3. Each side of the plate is smooth and flat, and the edges of the plate are also smooth, and both sides of the plate are substantially alike.

What I claim is—

The design for a kettle-scraper substantially as shown and described.

In testimony whereof I have hereunto set my hand this 29th day of January, A. D. 1897.

MINNIE K. NORTON.

In presence of—

A. C. PAUL,
M. E. GOOLEY.
